UNITED STATES PATENT OFFICE

156,664

BUTTOCK REST

Lillian Richards, Washington, D. C.

Application August 14, 1947, Serial No. 140,875

Term of patent 14 years

(Cl. D15—8)

To all whom it may concern:

Be it known that I, Lillian Richards, a citizen of the United States, residing at Washington, District of Columbia, have invented a new, original, and ornamental Design for a Buttock Rest, of which the following is a specification, reference being had to the accompanying drawing, forming a part thereof.

Fig. 1 is a top plan view of a buttock rest disclosing my new design.

Fig. 2 is a side elevation.

Fig. 3 is an end view.

Fig. 4 is a view taken along the line 4—4 of Figure 2.

Fig. 5 is a perspective view of the frame of the buttock rest.

I claim:

The ornamental design for a buttock rest, as shown.

LILLIAN RICHARDS.
